UNITED STATES PATENT OFFICE

BENJAMIN J. BUTLER, OF SOMERVILLE, MASSACHUSETTS, ASSIGNOR TO WIRELESS SPECIALTY APPARATUS COMPANY, OF BOSTON, MASSACHUSETTS, A CORPORATION OF NEW YORK

CONDENSER MANUFACTURE

Application filed November 16, 1926. Serial No. 148,665.

The invention hereof relates to the assembly of electrical condensers and more particularly those of the application of John A. Proctor, Serial Number 54,190, filed 3 September 1925 and of myself, Serial Number 111,683, filed 26 May 1926. But the subsequent disclosure in the present case is only that of said Proctor application.

The object of the invention is the economical production of good condensers, particularly in respect of the labor charge which is the largest portion of the factory cost of condensers of the type which the invention is intended to produce.

The invention consists of the improvements in apparatus for manufacturing and of improvements in manufacturing condensers of the general type in question, which improvements are described hereinafter and specified in the claims, the description being aided by the drawings of which

Fig. 1 is a side elevation, partly in section, of a condenser of one of the types to be manufactured, this figure illustrating conditions just prior to the final step in the manufacture; but exaggeration in the height of the stack having been made for clearness;

Fig. 2 is a front elevation of a hand-riveting machine, showing in cooperative relation therewith, the assembling device of Figs. 3-5.

Fig. 3 is a fragmentary enlarged section of a portion of the assembling device of Fig. 5, illustrating the condenser of Fig. 1 in process of manufacture;

Fig. 4 is a plan of the assembly device of Fig. 5;

Fig. 5 is a central vertical section of the assembly device, which eventually is placed in the riveting machine of Fig. 2;

Fig. 6 is a top perspective view, illustrating the condenser of Fig. 1 after the riveting operation of the apparatus of Fig. 2; and

Fig. 7 is a modified form of the condenser of Figs. 1 and 6, which can be made in the apparatus of Figs. 2-5.

The elements of the condenser are assembled by the operative in the device of Figs. 3-5; thereafter said device with the condenser therein, is transferred to the machine

of Fig. 2 and therein the rivet head A of Fig. 1 is upset as shown at V, Fig. 6.

In assembling the condensers of Figs. 1 and 7 in the device of Figs. 3-5, the operative places the condenser parts in said device, working upwardly from the bottom of Fig. 1, i. e., first the rivet A, and then successively, the bottom metal clamp B, insulating (mica) sheet C, then alternately the armature foils and intervening dielectric (mica) sheets, metal connection-plate Q, foil-folds from the left, insulating (mica) sheet R, metal connection plate S, foil-folds from right, insulating (mica) sheet T, and top metal clamp U.

Then, in order to upset the top end of the rivet, the assembly device is transferred to the riveting machine of Fig. 2. After such riveting, the assembly device is removed from the riveting machine, the finished and riveted condenser removed from the assembling device, and the latter used again and repeatedly as the means of assembling additional condensers.

The apparatus of Figs. 2-5 is useful in making other forms of condensers, including that of Fig. 7, which is like that of Figs. 1 and 6 save that the only armatures are the connection plates Q, S, without any foils as in Figs. 1 and 6. In the condensers of Figs. 1, 6, and 7, the connection plates project laterally from the stack as shown at tabs W and X, Fig. 6. The assembly process for the condenser of Fig. 7 is the same as that for the condensers of Figs. 1 and 6, save only for the laying of the foils in Figs. 1 and 6 and bending them up, over and down upon the connection plates Q and S around stud or rivet A.

In the condenser of Figs. 1 and 6 the foils are about double usual length, and after the stack is built, the projecting bunches of foils on opposite sides of the stack are bent or folded upwardly and down upon the respective connection plates Q and S.

If the superficial dimensions of clamping plates B and U are sufficiently small, and they are of steel or thick enough not to bend up at their edges, the central rivet A will hold the structure under constant pressure to maintain constant capacity and the desired other

clamping functions. In any event, the operation of upsetting the upper end of rivet A is such as to put the condenser stack under the desired mechanical pressure. Altho plates 5 B and U may be of sheet metal, they should not be of such nature as to permit their peripheries to bend away from the stack upon riveting at the center, to an extent sufficient to permit substantial loosening of the condenser elements. But the invention may be employed in connection with any desired means of maintaining stack pressure, with any desired form of plates B and U, separately or jointly, and any desired means for forcing them together.

15 The assembly operations are illustrated in a practical way in Figs. 2-5. Heretofore the manufacture of this general class of condensers has included building of the condenser stack by girl operatives, and temporary clamping of the same by them to permit transport of the incomplete condensers to a more or less distant power machine which applied permanent clamps or clamping means, or both. This invention, however, involves 20 an entirely different system of factory production; i. e., it permits the entire completion of the condenser, including permanent clamping, by the same girl operatives who build the stack, or at least permits permanent clamping 25 of the condenser without removing it from its assembly device, this being advantageous in eliminating the step of temporary clamping and transfer to a more or less distant finishing or riveting machine, or first removing 30 the condenser from its assembly device prior to such transfer, thereby reducing cost and insuring against disassembly of the various elements of the condenser.

In Fig. 2 is illustrated a small riveting machine, which is secured to a bench or table between two adjacent girl operatives, both of whom are engaged in building the condenser as in Figs. 1 and 6, or 7. Such two operatives never complete the assembly of a condenser at 40 the same instant, and each, as soon as a condenser is assembled, operates handle 23 of the riveting machine of Fig. 2 to upset the upper end V of rivet A as the final operation, as illustrated in Fig. 6. The condenser assembly, 45 however, is performed in the separate movable assembling device 14, shown in Figs. 3-5, each operative being provided with one of these devices 14, which is located on the bench in front of her during the assembly operation. 50 When a condenser has been assembled in this device, separate from the special riveting machine, Fig. 2, the operative transfers it to the lower part of that machine, centralizing the device 14 under riveting pin 9 by placing device 55 14 inside of guide plates 24; and then operates handle 23 to depress pin 9 and upset the top of rivet A, the complete condenser being ejected from device 14 after this operation by outer movement of trip 11 caused by the 60 operative's thumb. The operative then re-

moves her own assembling device 14 from the machine and restores it to the bench directly in front of her to begin assembly therein of the next condenser, leaving the machine of Fig. 2 ready to receive the duplicate assembly 70 device of her co-operative.

The assembly of the condenser in the assembling device 14 of Figs. 3-5, by one operative, in accord with the structure and operations illustrated in Figs. 1 and 6, or 7 is as 75 follows:

1st: Eyelet A (Fig. 1) is put over pin 1 of the assembly device (Fig. 5), its end which is already upset being down, and pin 1 projecting up thru the eyelet.

2nd: Centrally perforated lower clamping plate B (Fig. 1) is put over and around rivet A around central pin 1 (Fig. 5), the central perforation of B approximately fitting around rivet A (Fig. 1). Up to the time 85 of the final operation, i. e., riveting the pin 1, in eyelet A, holds the growing stack to a fixed center. Guide-posts 27 (Fig. 4) hold rectangular clamping plate B in alinement.

3rd: Centrally perforated insulating separator C (Fig. 1) is put over and around rivet A, its central perforation approximately fitting around the rivet. Guide-posts 27 (Fig. 4) hold separator C in alinement with 90 clamp plate B.

4th: A righthand lead foil (Fig. 1) is laid over and around eyelet A and righthand guide-pin 2 (Fig. 5). The righthand end of such foil is laid between guide-plates 25 (Fig. 4). The lefthand end is laid between 100 posts 27. Said foil has two perforations, both of like diameter, and larger than eyelet A, Fig. 1. Said foil is laid down and around eyelet A so that the edge of its lefthand hole passes around (and is spaced from) eyelet A (Fig. 1) and the edge of its righthand hole engages and fits over pin 2 (Fig. 5) of the assembly device, said foil-hole being the same diameter as pin 2. This operation 105 spaces the foil from left to right with respect to central rivet A, the left hand hole being centralized relative to the rivet, by guide-pin 2 and guide-plates 25, said hole being substantially larger than the diameter of the rivet 110 (Fig. 2) in order to space and thereby insulate the foil therefrom. Pin 2 is inclined at its outer side, as shown, Fig. 5, to facilitate the passage around it of the edge of the right hand hole in the projecting end of the foil. Each righthand foil has one large electrical 115 clearance hole for stud or rivet A and a good fit hole for the pin 2, irrespective of whether the two foil-holes are of equal diameter, as is shown and preferred.

5th: A centrally perforated mica dielectric, 125 Fig. 1, is then laid down around rivet A around pin 1 in Fig. 5, between posts 27, Fig. 4. The central hole in the mica sheet is substantially smaller than the holes through the foil-sheets, this hole being such as to permit 130

- stud or rivet A to fit, but not too tight, in the mica. Since the foils are spaced from eyelet A, the central edge of the mica constitutes an insulating margin projecting inwardly from adjacent foils.
- 5 6th: A lefthand foil-sheet is put in place in the assembly device 14 of Fig. 5, its right-hand hole surrounding eyelet A on pin 1, and spaced from A; and its lefthand hole, engaging around left-hand guide-pin 3, Fig. 5, which is a duplicate of righthand pin 2, but inclined in the opposite direction. The left-hand end of the foil is laid between guide-plates 26 (Fig. 4), thereby, in cooperation with guide-pin 3 and guide-posts 27, centralizing righthand foil-hole around eyelet A. All the foils, right-hand and lefthand, have the same two cut-holes near their respective ends.
- 10 7th: Mica-sheet operation "5th", above, is repeated. All the mica sheets are laid directly above one another in the stack (Fig. 1), between guide-posts 27, Fig. 4.
- 15 8th: A second righthand foil-sheet is laid as in above operation "4th". Alternate foils project from opposite sides of the stack.
- 9th: Operation "5th" is repeated for a mica dielectric.
- 20 10th: A second lefthand foil is laid as in above operation "6th"; and this laying of righthand foils, micas, and lefthand foils is continued up to the laying on of lower connection plate Q, Fig. 1, at top. All these operations are conducted on top of assembly device 14 of Fig. 3-5, all the condenser parts being perforated and held at a fixed center until the final operation of riveting.
- 25 11th: The stack and condenser as thus far assembled on compressible table 16 of the device 14 of Fig. 5, with the elements as in Fig. 1 and foils projecting left and right horizontally, are pressed down by the operative's fingers against spring 12 around plunger 15 carrying table 16. Latch-pin 4, pressed by spring 17, then shoots into lateral hole 5 in table 16, thereby holding the condenser, table 16 and plunger 15 down, the table and condenser lying in well 18 in main block 14, as shown in Fig. 3. This downward movement forces into more or less upright positions, shown in Fig. 3, the groups of lefthand and righthand foils projecting from the stack; these foils being first lifted up and off from pins 2 and 3. That is, the downward movement of table 16 into the depression or well 18 in assembly block 14, carries the stack down also and causes the ends of the projecting foils to be slid inwardly up the inclines of pins 2 and 3 and off said pins, and causes the intermediate portions of the foils to engage against the opposite side walls of well 18, so that as table 16 moves downward the projecting foils are forced up from the horizontal positions in which they have been stacked, to the more or less vertical positions
- 30 shown in Fig. 3, thereby making it unnecessary for the operative to perform the difficult feat of picking up the ends of the fragile foils with her fingers from a horizontal position lying on the flat top surface of assembly device 14 as in Fig. 5.
- 35 12th: Table 16 and the partially completed condenser being in the lower position, with table 16 held down by latch 4, the first connection plate Q, Figs. 1-7, is laid on top of the stack, its tab W being laid (Fig. 4) in a depression 28 between two posts 27, and the smaller hole Q1 in tab W (Fig. 6) engaging around a pin 29 fixed in the floor of depression 28. The main part of connection plate Q is alined by the two pairs of guide-posts 27, and pin 29 centralizes the larger hole of Q (Fig. 1) around eyelet A on center pin 9, so that the connection plate Q is insulated from the eyelet A.
- 40 13th: Thereupon the operative, with her fingers, folds down the ends of the lefthand foils to the right (Fig. 1), from the vertical position of Fig. 3, so that lefthand foil-holes are centralized around smaller eyelet A, Figs. 1 and 4.
- 45 14th: Then intermediate insulating sheet R, Fig. 1, and upon that the upper connection plate S, are laid on top of the lefthand foils which have been folded down by the preceding operation. Sheet R is alined between the two pairs of guide-posts 27 (Fig. 4). Plate S is guided similarly to plate Q of the 12th operation, its tab X, Fig. 6, being laid in a depression 30 between two posts 27, the pin 31 engaging in the hole X1 in tab X of plate S, Fig. 6. The stack now is ready (vertical in Fig. 3), to have the righthand foils folded over on top of connection plate S.
- 50 15th: Then the operative with her fingers (Fig. 4) folds down the projecting ends of the righthand foils, Fig. 3, so that they assume the position shown in Fig. 2; and she centralizes the holes in the folded down foils, around rivet A.
- 55 Note: The stack of Fig. 1 is adapted for capacities up to .005 mfd.; but above that capacity the stack will have greater thickness. In order to assemble such a thicker stack in the same condenser, i. e., including use of foils having the same spaced holes, the above operations may be modified as follows. Upon completion of the stack and before the application of the first or lower connection plate Q, the first group of projecting foils may be folded over upon the stack. This permits the holes thru the projecting and folded portions of the foils to be centralized around eyelet A, notwithstanding the slight increase in stack thickness for higher capacity. Then connection plate Q may be laid and upon it insulating sheet R (Fig. 1). Then the other set of foils is folded over in assembly device 14, permitting centralizing of their holes
- 60 65 70 75 80 85 90 95 100 105 110 115 120 125 130

around eyelet A, and on them then is laid insulating separator T.

16th: Then top insulating sheet T, Fig. 1, is laid on top of the folded-over horizontal portion of the righthand foils, being alined by eyelet A and the posts 27, Fig. 4, and the side walls of well 18 in block 14.

17th: Then top clamping plate U is laid on sheet T around eyelet A around pin 1, Fig. 4.

18th: Then the assembly device 14, Fig. 5, a part of which is shown enlarged in Fig. 3, is transferred by the operative from a position in front of her to the position on the base 18, as shown in Fig. 2, and centralized underneath the plunger 7 of the riveting machine by insertion of block 14 within guide-plate 24. As shown in Fig. 3, table 16 and the condenser are held down in well 18 of assembly block 14, the condenser, pending the final operation of upsetting eyelet A, being laterally held in assembly by the walls of well 18, the terminal tabs of the condenser being held in depressions 28, 30, Fig. 4.

19th: The operative, by pulling down handle 23, Fig. 2, operating on pivot 6, forces down plunger 8, which carries riveting pin 9 at its lower end. Pin 9 and the other parts shown at the lower end of plunger 8 move down toward the condenser in their relative positions as shown, with pin 9 projecting below plate 7, and the lower end of plunger 8 slightly above the lower surface of plate 7. Four screw-bolts 20, surrounding plunger 8, are screwed into plate 7, but extend free thru member 22 set at 32 on plunger 8. Springs 19 surround bolts 20, and additional springs 21 are located between member 22 and plate 7. Upon operation of handle 23, first, pin 9 enters in eyelet A, eventually depressing pin 1 against spring 10 (Fig. 5) and replacing pin 1. Next, plate 7 engages the top of the condenser which quickly slows up the movement of plate 8 relative to that of pin 9 and plunger 8, which continue their uniform downward movement (while plate 7 is increasing the pressure, via springs 19 and 21, on the stack) until the upper tapered portion of pin 9 engages the top of eyelet A and up-sets it. In this operation, plate 7 is nearly stationary and the lower portion of plunger 8 moves down, member 22 sliding down along bolts 20. Plate 7 compresses the condenser to the desired final pressure, and maintains it until the upset of the eyelet takes over this function. The operative then releases handle 23 and pin 1 springs up into the eyelet A.

20th: The condenser now being completed, the operative pulls out rod 11 of the assembly block 14, Fig. 2, releasing latch-pin 4, Fig. 5, from table 16, allowing spring 12 to shoot table 16 up and eject the completed condenser from the assembly block 14.

21st: The operative then removes assembly

block 14 from the riveting machine of Fig. 2, replaces it in front of her in position convenient for building the next condenser, thereby leaving the riveting machine free to have inserted in it, by the adjacent operative, another duplicate assembly block 14 carrying a condenser completed save for the riveting operation.

22nd: The structurally completed condensers as they are ejected, in Fig. 2, from the assembly block 14, after riveting, then are treated finally in preparation for service, are tested for voltage breakdown and capacity, and are then ready for the market. The treatment may include any well-known boiling in hot paraffin under a vacuum, if desired.

If desired, the operation of folding down the foils from the vertical positions shown in Fig. 2 may be aided by any suitable mechanism, just as the operation of picking up the foils to the vertical positions shown in Fig. 3 is effected by the mechanism of the assembly block 14. But it is usually sufficient, as shown, to enlist the aid of mechanism for picking up the foils (Fig. 3) and to leave the folding down of the foils to the fingers of the operative. It is desirable to effect the machine operation of Fig. 3, as the preferred method of elevating the foils to their positions shown, on account of their fragile nature, because of the consequent difficulty in picking them up by the fingers from the horizontal positions in which they have been stacked initially, especially having in mind that actually the foils projecting outside the stack lie close together in a thin fragile bunch as distinguished from the exaggerated separation of Fig. 1, and that they lie down close to the surface of the assembly block. When once the foils are more or less elevated, as in Fig. 3, it is not difficult for the two bunches of foils to be engaged by the fingers of the operative to push them down toward the rivet or compression stud and centralize them, because, as distinguished from the stacked foil-position where the foils lie flat on the assembly block and require to be picked up, on the other hand in the foil-positions shown in Fig. 3 their ends are more or less free in the air in position to be folded down as distinguished from being picked up for upward folding.

The hollow or well 18 of the block 14 of Figs. 3-5 is formed to receive the entire condenser, when table 16 is depressed, i. e., is formed with depressions 28, 30 (Fig. 4), so as to permit the free downward passage of projecting terminals or tabs W, X (Fig. 6). These projecting terminals may be of any desired shape, and depressions 28, 30 (Fig. 4) are shaped accordingly.

In the riveting machine of Fig. 2, the spring plate 7 is designed relative to riveting pin 9, so that plate 7 holds the condenser built up around pin 1 at the desired mechanical com-

pression at the instant when eyelet rivet A is upset, so that its upper portion V engages upper clamp U, which thereafter maintains the desired compression and, therefore, a constant capacity, in connection with the subsequent waxing treatment.

The eyelet rivet A, as a compression stud, may be a solid rivet, or the condenser may be completed without the use of any riveting machine but with the assembly block 14, when such compression stud consists of a bolt with a nut in place of an upset rivet. With such form of central compression stud, the capacity of the condenser can be adjusted by screwing up the nut.

Preferably, as shown in Figs. 1 and 6 (but not necessarily), the connection plates Q and S, with their terminal tabs W and X, are located at right angles to the oblong foils, i. e. the tabs W and X project from the sides of the stack from which the foils do not project. The advantage of this is that the guide pins 2 and 3 of assembly block 14 of Fig. 5 can be permanently fixed, the tabs W and X being carried down into the depressions 28, 30, of block 14 when the partially completed condenser on table 16 is pressed down to force up the projecting foils from off the pins 2 and 3 to the more or less vertical positions (Fig. 3) which will facilitate subsequent manual folding down of the foils on top of the condenser stack. That is, the above-described relation between the tabs W and X and the projecting foils of opposite polarity permits the perforated foils being placed over the fixed pins 2 and 3, and yet leaves the rest of the condenser free, including tabs W and X, to be depressed in order to push the foils up from off the pins 2 and 3.

The advantages of the invention are that when the parts of the condenser have been assembled in their operative positions and when they would be disturbed from such positions by removal from the assembly device, their transfer to the riveting machine without removal from the assembly device, permits the parts to be retained permanently in the operating positions in which they have been carefully stacked manually by the operative; and the provision of a single riveting machine constructed and arranged to cooperate successively with each of a plurality of neighboring assembly devices in which the condensers have been assembled, is advantageous in that it permits substantially simultaneous manual assemblage of a plurality of condensers by a plurality of operatives, and the alternative use of the same riveting machine by the same operatives who are assembling the condensers, without requiring even such disturbance of the condenser parts as would be liable to be involved by transfer of the assembled condensers in the assembly devices from the place of assembly to a distant point and/or from the

assembly-operatives to a transferring or riveting operative. This method has the novel merit in condenser manufacture that it centers all responsibility for finally operative condensers upon a single operative who both assembles and finally clamps by riveting; and the invention provides the means whereby this can be done without compelling the operative to leave her place and without requiring expensive power-driven riveting machinery in multiple for every two or three operatives. The cost of all of a large number of little hand-riveting machines of Fig. 2 which serves for two or more operatives, is substantially no greater than the power machines heretofore in use for riveting condensers assembled by the same gross number of operatives. A larger portion of the economy effected by that invention is in the assembly of the condensers in the assembly devices; but a very important economy results in the insurance against inferior or inoperative condensers due to mis-placement of parts between completion of assembly and final clamping.

I particularly point out and distinctly claim the part, improvement or combination which I claim as my invention or discovery, as follows:

1. An assembling device for an electrical condenser having projecting foils to be folded over on top of the stack, which comprises a building surface including outer stationary portions and an intermediate depressible support adjacent the stationary portions; foil-aligning means; and a device locking said support in its depressed position.

2. An assembly device for an electrical foil condenser, which comprises a block having a central stack-well; foil-guides on said block beyond opposite sides of said stack-well; and a stack-carrier depressibly mounted in the stack-well.

3. An assembly device for an electrical foil and mica condenser, which comprises a block having a central stack-well; foil-guides on said block beyond opposite sides of said stack-well; mica-sheet guides at the other two opposite sides of said stack-well; depressions in said block communicating with said stack-well and located at the same opposite sides of the well where said mica-guides are located; and a stack-carrier depressibly mounted in the stack-well.

4. An assembly device for a capacitor stack comprising a support, guide means for layers of dielectric material, and guide means for layers of foil which project from one side of said stack, said support being shaped to facilitate engagement with the underside of said projecting foil at a distance from said stack for raising said projecting foil with respect to the foil within the stack.

5. An assembly for a capacitor stack comprising a support, means thereon for ver-

tically positioning a rivet, guide means for layers of dielectric sheets perforated to receive said rivet, and guide means to position layers of foil around said rivet and stacked with said sheets but out of contact with the rivet by cooperation of a portion of the foil laterally projecting beyond said stack on one side.

6. An assembly for a capacitor stack comprising a support, guide means for superposing layers of foil and dielectric material thereon in a stack with the foil extending beyond one edge of the dielectric material, the portion of said support under the projecting foil being movable with respect to the portion of said support under the stack to facilitate raising the projecting foil layers from said support.

7. The process of erecting a condenser stack which comprises separately aligning a plurality of armatures and dielectric members with the armatures extending beyond the dielectric members on opposite sides and simultaneously moving the armatures for bending them adjacent the stack sides.

In testimony whereof I hereunto affix my signature.

BENJ. J. BUTLER.
